UNITED STATES PATENT OFFICE.

EDWIN G. BATES, OF NEW YORK, N. Y., ASSIGNOR TO THE BATES MACHINE COMPANY, OF NEW YORK, N. Y., A CORPORATION OF NEW JERSEY.

NUMBERING-MACHINE.

SPECIFICATION forming part of Letters Patent No. 789,113, dated May 2, 1905.

Application filed July 7, 1904. Serial No. 215,612.

To all whom it may concern:

Be it known that I, EDWIN G. BATES, a citizen of the United States of America, and a resident of the city, county, and State of New York, have invented certain new and useful Improvements in Numbering-Machines, of which the following is a specification, reference being had to the accompanying drawings, forming a part thereof.

10 My invention relates to improvements in numbering-machines, and particularly to automatic hand numbering-machines.

My invention consists in certain improved mechanism for controlling the operation of 15 the shifting movements given to the numbering-wheels upon each reciprocation of the machine for a printing operation, so that the machine may print numbers consecutively, in duplicate, or may repeat the same number in 20 definitely.

The objects of my invention are to simplify mechanism for this purpose and to render the operation thereof accurate and positive, to provide means whereby it may be instantly 25 discernible as to how the machine is adjusted—that is to say, whether it is adjusted for “repeat,” “consecutive,” or “duplicate” printing—and to so design and construct the parts that they shall be simple and easy of manufacture and unlikely to get out of order.

My invention also consists in certain details of construction and novel combination of parts, as will hereinafter be more fully pointed out.

35 I will now proceed to describe a numbering-machine embodying my invention and will then point out the novel features in claims.

In the drawings, Figure 1 is a view in front elevation of a numbering-machine embodying 40 my invention. Fig. 2 is a view in rear elevation of the same. Fig. 3 is a view in side elevation with the stationary body portion of the frame in transverse section. Fig. 4 is a similar view with the parts shown in their 45 depressed or printing positions. Fig. 5 is a transverse sectional view, on an enlarged scale, showing the numbering-wheels and the actuating and controlling mechanism therefor.

Fig. 6 is a top view of the parts shown in Fig. 5, certain parts being broken away in order 50 to show other parts beneath them. Fig. 7 is a detail view, on an enlarged scale, of one of the numbering-wheels employed. Figs. 8 and 9 are detail views illustrating the action of the controller in setting the machine for indefinite 55 repeat. Fig. 10 is a face view of a curved plate employed in connection with the controller. Figs. 11 and 12 are face and edge 60 views, respectively, of an idler-wheel employed.

The framework of the machine comprises an inverted-U-shaped body portion 1, a tubular stem 2, uprising therefrom, and a base-plate 3. The wheel-carrier comprises a wheel-carrying frame 4 and an operating-stem 5. 65 The operating-stem passes through a perforation in the U-shaped body portion of the stationary frame and extends upward through the tubular extension 2. To the upper end of the stem 3 is secured an operating-handpiece 70 6. The said handpiece is counterbored at 7 to receive the upper end of the tubular extension 2, and a coiled spring 8, coiled around the stem 5, bears at one end against a shoulder formed in the stationary frame and at the 75 other end against a shoulder formed at the base of the counterbore 7. The stem 2 and handpiece 6 completely inclose the spring and stem, forming a housing therefor. When the handpiece 6 is depressed to depress the wheel-carrier, the tubular extension 2 is received within the counterbore 7, within which the stem is allowed to slide freely.

The wheel-carrier 4 supports a wheel-shaft 9, the ends of which project beyond the frame 85 of the wheel-carrier and are received within grooves 10, formed in the inner faces of the legs or standards of the body portion 1 of the stationary frame. This forms a guide for the wheel-carrier in its reciprocating movements 90 and prevents the same from turning. The wheel-shaft in the present construction is secured in the frame against rotation, a set-screw 11 holding it in position. A plurality of numbering-wheels 12 are rotatably mounted upon 95 the stationary wheel-shaft 9, each numbering-

wheel comprising a disk having printing-numbers on its periphery and ratchet-teeth by which the said wheels may be rotated, there being one ratchet-tooth for each number on 5 the periphery and one of the series of teeth being a deep tooth, as is common in this connection. In addition to the six numbering-wheels here employed there is an idler-wheel 13 rotatably mounted upon the shaft 9, said 10 idler-wheel having alternate deep and shallow ratchet-teeth. The numbering-wheels are each provided with stop-pawl 14, which engage their ratchet-teeth, and a similar stop-pawl 15 engages the ratchet-teeth of the idler-wheel 13. A comb-spring 16 presses on the 15 pawls 14, causing them to bear with yielding pressure against the ratchet-teeth of the numbering-wheels. A pawl 15 is provided with a wire spring 17, tending to force it toward 20 the idler-wheel 13, with the teeth of which it is adapted to engage.

The operating-pawls for the ratchet-wheels are carried by a rocking member 18, said rocking member pivoted to the stationary frame 25 of the machine by means of pivots 19. This rocking member is operated by means of rocker arms or links 20, which are freely mounted upon the wheel-shaft 9 and are pivotally connected at their outer ends upon a 30 bar or spindle 21, carried by the said rocking member. The operating-pawls 22 are hung upon this bar or spindle 21 and are spring-pressed toward the numbering-wheels by means of a coil-spring 23. The operating-pawls 22 comprise a bar having a plurality of teeth 24 of various lengths, which teeth are adapted to engage the ratchet-teeth of the numbering-wheels. The teeth 24 are progressively longer, so as to act as transfer devices 35 at each complete revolution of any one wheel. This arrangement and construction is well known in this art, and any further detailed description of the operation thereof is unnecessary. In addition to the teeth 24 the pawl-bar 40 also carries a tooth 25 for engagement with the idler-wheel 13. The length of the tooth 25 is such that when it is in engagement with any of the shallow teeth of the idler-wheel 13 the remainder of the pawl-teeth 24 45 will be held clear of engagement with any of the ratchet-teeth of any of the numbering-wheels. When, however, tooth 25 is received within one of the deep teeth of the idler-wheel 13, the pawl-teeth 24 will then be free to engage the ratchet-teeth of the numbering-wheels just as if the idler-wheel and the tooth 25 were not present.

Loosely mounted upon the wheel-shaft 9 is a controller 26, said controller comprising 60 two arms 27 and 28, arranged upon the shaft at opposite ends of the numbering and idler wheels, and a curved plate 29. The arm 27 has three notches in its periphery, 30, 31, and 65 32, the surfaces between the notches being inclined, so as to form, in effect, cam-surfaces.

The notch 31 is a shallow notch, while the notches 30 and 32 are relatively deep. The arm 27 is arranged immediately between the idler-wheel 13 and the frame 4 of the wheel-carrier, and the pawl 15, which engages the idler-wheel 13, is provided with a pin or projection 33, arranged to engage the said notches. When the pin or projection 33 is received within either of the notches 30 or 32, the stop-pawl 15 will be free to engage the idler-wheel teeth; but when the arm is so turned as to cause the pin or projection 33 to be received within the notch 31 the pawl will have been forced out of engagement with the teeth of the idler-wheel 13 and will be held out of such engagement for so long a time as the pin or projection remains in the said notch. The other arm, 28, of the said controller has a cam projection 34, which in certain positions of the controller is adapted to engage or be engaged by the first pawl-tooth 24 of the pawl-bar 22. It will be noted that this first pawl-tooth 24 is wider than the others, so that it will not only engage the ratchet-teeth of the first numbering-wheel, 90 but it will also overhang same, so as to be in a position to engage or be engaged by the cam projection 34, the arm 28 being located, as will be noticed, between the first numbering-wheel and the frame 4 of the wheel-carrier. 95 In the present construction the position of the cam projection 34 is such as to engage or be engaged by the pawl when the controller is turned to cause the pin or projection 33 to engage the notch 32 in the arm 27. The cam projection 34 at this time acts as a blank to prevent the first pawl-tooth 24 from engaging the teeth of the first ratchet-wheel, and as the first pawl-tooth is the longest it consequently prevents all the teeth from engaging any of the ratchet-wheels, so that with the controller in this position reciprocation of the actuating-pawls will effect no movement whatsoever of the numbering-wheels. In any other 105 position of the controller 26 the cam projection 34 will be moved so as to be out of the way of the first pawl-tooth 24, and the pawl-teeth will be permitted freely to engage their respective ratchet-wheels.

The wheel-carrier is provided with an overhanging curved shield 35, to which is fitted the curved plate 29. The shield 35 has a window 36 cut therein, through which a portion of the face of the curved plate 29 may be seen. The curved plate has the words "Repeat," 11 "Consecutive," and "Duplicate" printed, engraved, or otherwise indicated thereon, and in the various positions of the controller the portions of the plate bearing these different words are arranged to be brought opposite 12 the window in accordance with how the controller is set, so that the condition of the machine—i. e., whether the machine will print consecutively or in duplicate or will repeat—will be instantly discernible to the operator. 13

The curved plate 29 is provided with two projecting lugs or extensions, as shown, upon which are secured handpieces or knobs 42, by which the controller may be conveniently 5 operated by hand. These knobs or finger-pieces project upwardly to the side of the shield 35, as clearly shown in Fig. 1, rendering them easily accessible. When the hand-piece 6 and wheel-carrier 4 are depressed for printing operation, the arms 20 will be partially rotated around the shaft 9 by reason of their pivotal engagement 21 with the rocking member 18, the rocking member 18 being rocked about its pivotal supports 19 at this 10 time. The pawl-bar 22 being hung upon the spindle 21, supported between the rocking member and the arms 20, will be moved rearwardly with respect to the numbering-wheels to engage a fresh tooth thereon, and upon a 15 return movement of the wheel-carrier such pawl-teeth as have engaged ratchet-teeth of the numbering-wheels will give a single step-by-step movement to such numbering-wheels to advance them a single unit. The pawls 20 will so actuate the numbering-wheels after each printing operation when the controller is in its intermediate position, the notch 31 engaging the pin or projection 33 upon the stop-pawl 13 of the idler-wheel, leaving the 20 idler-wheel entirely free. At this time the word "Consecutive" upon the curved plate 29 will show through the window 36 of the shield 35. During this time the pawl-tooth 25 upon the pawl-bar 22 will be received 25 within one of the deep notches of the idler-wheel, and the stop-pawl being out of engagement therewith the idler-wheel will move backward and forward idly during the actuating movement of the pawl-bar, so that 30 the pawl-teeth 24 will be free to engage their respective numbering-wheel ratchet-teeth. So long as the controller remains in this position the numbering-wheels will be rotated progressively step by step at each printing operation of the machine. When the controller is moved upward, so as to bring the word "Duplicate" thereon opposite the window 36, the pin or projection 33 on the idler stop-pawl 15 will be released from the notch 31 and will 35 drop into one of the deep notches 30. When in this position, the stop-pawl 15 will be free to engage the teeth of the idler-wheel 13, so as to prevent any rearward or return movement thereof. With the parts in this position each reciprocation of the wheel-carrier for a printing operation will cause the pawl-tooth 25 upon the pawl-bar 22 to alternately engage a deep or shallow tooth of the said idler-wheel, the pawl-tooth 24 being held out 40 of engagement with the numbering-wheel ratchet-teeth while the pawl-tooth 25 is engaging a shallow tooth of the idler-wheel 13 and the said pawl-tooth 24 being allowed to engage the numbering-wheel ratchet-teeth 45 when the pawl-tooth 25 is engaging a deep

tooth of the idler-wheel 13. At this time the printing operations will be in duplicate—that is to say, the same number will be printed twice in succession before the actuating-pawls will be permitted to move the numbering-wheels 50 to shift them forward one unit. In other words, while the actuating-pawls are reciprocated at each printing operation just as when the machine is set for consecutive printing they will be held in an inoperative position 55 during alternate printing movements. When the controller is moved in the opposite direction to a position in which the word "Repeat" upon the shield 29 comes opposite the window 36 of the shield 35, the cam-surface 60 34 will prevent the first or longest pawl-tooth 24 from engaging ratchet-teeth of the No. 1 numbering-wheel, so that while the actuating-pawls will be continuously reciprocated with respect to the numbering-wheels they will be 65 held out of operative engagement therewith and the wheels will remain in the positions at which they are set.

The ink-pad carrier 37 is carried by the rocking member 18, being pivotally supported 70 thereto at 38, and links 39 are pivotally connected at their lower ends by pivot-pins 40 with the said ink-pad carrier and at their upper ends by pivot 41 to the wheel-carrier frame 4. When the wheel-carrier is depressed for a printing operation, the ink-pad carrier will be swung downward and outward out of the path of movement of the numbering-wheels, being returned to its normal position 75 in engagement with the peripheries of the wheels upon the return movement of the wheel-carrier. The link engagement 39 will swing the ink-pad carrier downward and outward about the axis of its pivotal connection 80 38, while the rocking movement of the rocking member 18 will carry the same bodily still 85 farther outward.

It will be obvious that the foregoing is but an embodiment of my invention and that the same is capable of many and varied modifications within the spirit and scope of my invention and, further, that certain parts may be employed in connection with other parts of different construction. Hence I do not desire 90 to be limited only to the precise details of 95 construction and combination of parts herein.

What I claim is—

1. In a machine of the character described, the combination with a plurality of printing-wheels, an idler-wheel, actuating-pawls for said printing-wheels and idler-wheel, and a stop-pawl for said idler-wheel, of a controller comprising two arms arranged upon opposite sides of the said printing and idler wheels, and a yoke connecting the two arms across the said wheels, one of the said arms arranged in one position of the controller to engage the said stop-pawl, and to prevent its engagement with said idler-wheel, and the other of said arms arranged in another posi- 100

tion of the controller to engage the actuating-pawls and prevent their engagement with said printing-wheels.

2. In a machine of the character described, 5 the combination with a plurality of printing-wheels, a stationary shaft upon which said printing-wheels and idler-wheel are mounted, actuating-pawls for said printing-wheels and idler-wheel, and a stop-pawl for said idler-wheel, of a controller comprising two arms loosely mounted upon said shaft upon opposite sides of said printing and idler wheels, and a yoke connecting the two arms over the peripheries of said wheels, one of said arms 10 arranged to engage a projection on said stop-pawl and to be held impositively thereby in any of three positions in which it may be set, and in one of said positions to maintain said pawl out of engagement with the said idler-wheel, and the other of said arms arranged in one position of the said controller to prevent the engagement of said actuating-pawls with the said printing-wheels.

3. In a machine of the character described, 25 the combination with a plurality of printing-wheels, an idler-wheel, actuating-pawls for said printing-wheels and idler-wheel, and a stop-pawl adapted to engage said idler-wheel, of a controller including a rotatably-mounted 30 member having three notches, each arranged to engage said idler-wheel stop-pawl in different positions of the controller, one of the said notches arranged in a raised portion of the member, whereby the stop-pawl, when engaged therein, will be held out of operative 35 engagement with the said idler-wheel.

4. In a machine of the character described, the combination with a plurality of printing-wheels, an idler-wheel, actuating-pawls for 40 said printing-wheels and idler-wheel, and a stop-pawl for said idler-wheel, of a controller comprising means in one position thereof for preventing the engagement of the said actuating-pawls with the said printing-wheels, and 45 in another position for preventing the engagement of said stop-pawl with said idler-wheel, said controller rotatably mounted about the axis of the said printing-wheels, and provided with a curved plate having thereon surface

marks indicating the various positions to which 5c the machine may be set, such marks arranged in the movements of the controller to register with a relatively stationary portion of the device.

5. In a machine of the character described, 55 the combination with a wheel-carrier, a wheel-shaft supported thereby, a plurality of printing-wheels mounted upon said shaft, an idler-wheel, also mounted upon said shaft, actuating-pawls for said printing-wheels and idler-wheel, and a stop-pawl for said idler-wheel, of a controller comprising arms mounted upon the wheel-shaft at opposite ends of the series 60 of wheels carried thereby, and a curved plate connecting the two arms beyond the peripheries of the said wheels, one of said controller-arms adapted to engage the actuating-pawls and prevent their operative engagement with the printing-wheels, and the other of said arms adapted to engage the stop-pawl for the idler-wheel, and prevent its operative engagement 65 with the said idler-wheel, the said curved plate having surface marks thereon indicating the 70 position to which the machine is set.

6. In a machine of the character described, 75 the combination with a wheel-carrier, a wheel-shaft supported thereby, a plurality of printing-wheels mounted on said shaft, an idler-wheel, also mounted on said shaft, actuating-pawls for said printing-wheels and idler-wheel, and a stop-pawl for said idler-wheel, 80 said wheel-carrier provided with a curved shield concentric with the axis of the said wheel-shaft, of a controller for said actuating means, said controller comprising a portion 85 rotatably mounted on said wheel-shaft, and a curved plate fitted to the curved shield of said wheel-carrier, said curved plate and shield having, the one surface marks thereon for indicating the various positions of the machine, 90 and the other a window for disclosing the said surface marks.

In witness whereof I have hereunto set my hand this 28th day of June, 1904.

EDWIN G. BATES.
